United States Patent Office

Des. 218,281

Patented Aug. 11, 1970

218,281

BOTTLE

Horst Diener, Ulm-Wiblingen, Germany, assignor to The Gillette Company, Boston, Mass., a corporation of Delaware

Filed Mar. 13, 1968, Ser. No. 10,960

Claims priority, application Germany Sept. 13, 1967

Term of patent 14 years

Int. Cl. D9—01

U.S. Cl. D9—71

FIG. 1 is a side elevational view of a bottle showing my new design, the opposite side being a mirror image thereof;

FIG. 2 is an end elevational view of the bottle, the other side being the same in appearance;

FIG. 3 is a top plan view of the bottle; and

FIG. 4 is a bottom plan view of the bottle.

I claim:

The ornamental design for a bottle, as shown and described.
